(57) **CLAIM**

The ornamental design for a remote controller for mobile device, as shown and described.

DESCRIPTION

FIG. 1 is a top perspective view of a remote controller for mobile device showing the new design; and

FIG. 2 is a bottom perspective view thereof;

FIG. 3 is a top plan view thereof;

FIG. 4 is a bottom plan view thereof;

FIG. 5 is a side elevation view thereof, wherein the opposite side elevation view is identical; and,

FIG. 6 is a front elevation view thereof, wherein the rear elevation view is identical.

The portions of the design shown in broken lines are unclaimed subject matter.
